UNITED STATES PATENT OFFICE

165,714

GRINDING MACHINE

Edward C. Hanna, Waynesboro, Pa., assignor to
The Thompson Grinder Company, Springfield,
Ohio, a corporation of Ohio

Application January 13, 1951, Serial No. 13,794

Term of patent 14 years

(Cl. D37—1)

To all whom it may concern:

Be it known that I, Edward C. Hanna, a citizen of the United States, residing at Waynesboro, in the county of Franklin, State of Pennsylvania, have invented a new, original, and ornamental Design for a Grinding Machine, of which the following is a specification, reference being had to the accompanying drawings forming a part thereof, wherein:

Fig. 1 is a side elevational view of a grinding machine, embodying my new design;

Fig. 2 is a perspective view showing the top, front and other side thereof;

Fig. 3 is a front perspective view, and

Fig. 4 is a rear perspective view thereof.

I claim:

The ornamental design for a grinding machine, substantially as shown.

EDWARD C. HANNA.
